UNITED STATES PATENT OFFICE.

EDWARD G. GROSS, OF COLUMBUS, GEORGIA.

PNEUMATIC PRESS AND METAL-FORMING MACHINE.

1,137,132.

Specification of Letters Patent. Patented Apr. 27, 1915.

Application filed March 30, 1914. Serial No. 828,174.

To all whom it may concern:

Be it known that I, EDWARD G. GROSS, a citizen of the United States, residing at Columbus, in the county of Muscogee and State of Georgia, have invented a new and useful Improvement in Pneumatic Presses and Metal-Forming Machines, of which the following is a specification.

This invention relates to improvements in 10 pneumatic presses and metal forming machines, and its object is to provide means for cheaply and easily straightening, bending and forming different kinds of metal, in either a hot or cold state, around shops in 15 general and railroad shops in particular. I fully attain this and other objects by the mechanism described and claimed and shown in the accompanying drawing, which forms a part of this specification.

20 This class of work around railroad shops has previously been done by heating the piece to be operated upon, and then hammering it into the desired shape; but this method is slow, laborious, expensive and 25 generally unsatisfactory, requiring skilled mechanics and in some cases special and expensive facilities for heating large pieces of metal.

With the machine here shown and 30 described all of the objectionable features of the work have been eliminated, and the cost reduced at least 50%, since it can be operated by cheap labor and the metal requires no heating.

35 The machine alone is used principally for straightening large sheets of metal which have been bent out of shape, but taken in combination with the different kinds and shapes of forming blocks it can be made to 40 do an almost unlimited variety of bending, shaping or forming metal.

Nothing in this drawing or specification, nor the fact that only two forming blocks are shown in the drawing, should be so construed as to limit the scope or variety of work which can be done on this machine, as the variety is only limited by the different designs of forming blocks which the operator cares to use.

50 In the drawings, Figure 1 is a full perspective view of my machine. Fig. 2 is a perspective view of the female die block for forming guard rails. Fig. 3 is a perspective view of the male die block for forming 55 guard rails.

Referring more particularly to the draw-

ing: 1 is a metal face plate to which are rigidly secured metal uprights 2, and to the top ends of the said uprights 2, transverse members 3 are rigidly secured. Transverse 60 bars 4 are rigidly secured to the said uprights 2, at a point between the said face plate 1 and the said transverse members 3, for the purpose of bracing the structure and affording means for locking the piston rod 65 5 in a stationary position. The said transverse bars 4, are provided with holes 6, spaced at intervals, into which metal rods 6^a are introduced for the purpose of holding the said piston rod 5, cylinder 10 and carriage 9 in a stationary position, which prevents the pressing block 7 from slipping to one side or the other when it happens to go down on a piece of metal which is bent 70 in such a shape as to form an inclined plane. 75

The structure of the machine is braced together by rods 8, which are attached to the said face plate 1 and the said transverse members 3 in such a manner that they hold the said uprights 2 exactly perpendicular to 80 the said face plate 1. A carriage 9 is adapted to traverse the length of the said transverse members 3, the top edges of which form a track for the carriage, and from this carriage the cylinder 10 is suspended 85 by an eye-bolt 11. The said carriage 9 and cylinder 10 are moved from one point to another between the extremities of the said transverse members 3, by means of a sprocket chain 12, secured to the said carriage 90 90 and running over sprocket wheels 13, to which motion is imparted by means of a hand chain 14 and a chain wheel 15, the said chain wheel 15 being fastened on the same shaft as is one of the said sprocket 95 wheels; and the said hand chain 14 is within easy reach of the operator, who may move the said carriage and cylinder at will.

The machine is operated by fluid pressure admitted at 16 into a controlling valve 17, 100 and from there it passes through conduit 18 and flexible tube 19 into the top end of the said cylinder 10, where it delivers a pressure in proportion to that of the main supply.

To relieve the pressure and raise the pressing block 7, fluid pressure is sent into the bottom end of the cylinder 10, through conduit 20 and flexible tube 21, while the dead air in the top of the said cylinder 10 110 passes to the atmosphere through flexible tube 19, conduit 18 and controlling valve 17.

The female forming block A (Fig. 2) is provided with a longitudinal channel *b*, to receive the bottom half of the base of a rail, a longitudinal channel *c*, to receive the bottom half of the ball of the said rail, and a longitudinal raised plane *d*, to support the web of the said rail. The top side of the said female forming block A is concaved to form a radius slightly greater than the radius of the said rail is to be after it is bent, so that the tendency of the rail to spring back when the pressure is removed, will be overcome.

The male forming block E (Fig. 3) is provided with a longitudinal channel *f*, to receive the top half of the base of a rail, a longitudinal channel *g*, to receive the top half of the ball of the said rail, and a longitudinal raised plane *h*, to engage the top side of the web of the said rail. The said male forming block E is constructed with the bottom side convexed to correspond with the concaved surface of the said female forming block A, and is secured to the bottom end of said piston rod 5, by means of a set screw 5^a, in such a position that the said channels in both the female forming block A and the male forming block E are parallel to each other.

To use the guard rail forming equipment, the female forming block, shown in Fig. 2, is placed across the face plate 1, while the pressing block 7 is removed, and the male forming block shown in Fig. 3 is attached to the piston rod 5 by means of a set screw 5^a; but other dies and forming blocks may be substituted and used in the same manner.

While the construction shown is the preferred form of the embodiment of my invention, I do not wish to confine myself to this exact construction, but desire the privilege of using any analogies or mechanical equivalents.

Having thus described my invention what I claim as new and desire to secure by Letters Patent is:

In a pneumatic press and metal forming machine, the combination of a face plate, upright members secured at each end thereof, transverse members secured at the top ends of the said upright members, a carrying member adapted to traverse the length of the said transverse members and support a cylinder, provided with a piston, a piston rod, means for applying, attaching and detaching forming members of various designs to the bottom end thereof, with means for applying a downward pressure to the said piston rod, means for controlling and releasing said pressure, means for moving the said carrying member and cylinder from one point to another along the length of the said transverse members, and means for maintaining the said carrying member and cylinder in a stationary position, substantially as shown and described.

In testimony that I claim the foregoing as my own I have hereto affixed my signature in the presence of two witnesses.

EDWARD G. GROSS.
